UNITED STATES PATENT OFFICE.

ERIK W. NELSON, OF NEW ROCHELLE, NEW YORK.

DESIGN FOR A MOTION-PICTURE CAMERA.

60,158.

Specification for Design.

Patented Jan. 3, 1922.

Application filed August 1, 1921. Serial No. 489,126. Term of patent 14 years.

To all whom it may concern:

Be it known that I, ERIK W. NELSON, a citizen of the United States, residing in the city of New Rochelle, county of Westchester, in the State of New York, have invented a new, original, and ornamental Design for a Motion-Picture Camera, of which the following is a specification, reference being had to the accompanying drawing,

forming a part hereof, in which a view in side elevation of the camera is shown.

What I claim is—

The ornamental design for a motion picture camera as illustrated.

This specification signed this 28th day of July, A. D. 1921.

ERIK W. NELSON.
